ATTORNEY

UNITED STATES PATENT OFFICE.

SAM NUSSEY, OF TRENTON, NEW JERSEY.

SLIDING DRAWER-DIVISION.

1,289,525.

Specification of Letters Patent. Patented Dec. 31, 1918.

Application filed April 9, 1917. Serial No. 160,762.

To all whom it may concern:

Be it known that I, SAM NUSSEY, a citizen of the United States, residing at Trenton, in the county of Mercer and State of New Jersey, have invented certain new and useful Improvements in Sliding Drawer-Divisions, of which the following is a specification.

This invention relates to a sliding partition for desk drawers and the principal object of the invention is to provide a device of this character which will occupy a minimum amount of space in the drawer.

Another object is to provide means whereby the device can be placed in the drawer and removed therefrom in a minimum amount of time and with the least possible effort.

Another object of the invention is to provide simple and efficient means for holding the partition in place while allowing the same to be quickly and easily moved to another part of the drawer.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described and specifically pointed out in the appended claims.

In describing my invention in detail, reference will be had to the accompanying drawings, wherein like characters denote like or corresponding parts throughout the several views, and in which:

Figure 1 is a longitudinal section through a drawer, provided with my invention.

Fig. 2 is a section on line 2—2 of Fig. 1.

Fig. 3 is a perspective view, showing the support for the partition.

Fig. 4 is a detail view of the track.

In this drawing, 1 represents the drawer having a slot 2 in its bottom, said slot being provided with a widened portion 2' in the rear of the drawer. 3 represents the track secured to the bottom of the drawer and composed of a bottom part 4 provided with the sides 5 and the flanges 6 secured to said sides, each of said flanges extending on both sides of the side members 5 and having the openings 6' in the outwardly extending part

to receive the screws 6* for securing the track to the bottom of the drawer and with the inwardly extending parts 6^a extending from the sides to the edge of the slot 2. The track stops at the widened portion of the slot, as shown in Fig. 1, and the flanges 6 are bent upwardly at an angle and are secured to the correspondingly inclined part of the bottom, as at 7. It will be seen that the flanges 6 are longer than the rest of the track, so as to provide for this upwardly inclined part.

The partition consists of the partition proper 8 secured in the fork 9 by the rivets 10. Said fork is composed of the stem 11 grooved to form the two members of the fork, as shown in Fig. 3, and said stem has an enlarged head 12 carrying the plate 13, said plate being connected to or formed with said head 12. Openings 14 and grooves 14' are formed in said head 12 adjacent the plate 13 and bars of spring metal 15 engage said grooves and have their ends passing through said openings to form springs for holding the partition against movement. The under face of the plate 13 is provided with corrugations, as at 16, which engage with corresponding corrugations 17 formed on the bottom plate 4 of the track.

When the partition is to be placed in the drawer, the plate 13 and head 12 are passed through the widened portion 2' of the slot 2, the inclined portion 7 of the flange 6 facilitating the passage of the springs 15 to the track. As the plate 13 reaches the proper level, the whole device is moved toward the front of the drawer, thus, the plate is held within the track, with the springs 15 bearing against the flange 6^a and tending to force the corrugations of the plate 13 into engagement with those 17 on the bottom plate 4. Thus, the partition will remain at any point it is placed and when it is desired to move the same, all that is necessary is to lift the partition with its stem slightly so as to compress the springs 15 and lift the plate 13 off the bottom plate 4. The partition can then be moved either forward or backward. As soon as the partition is released the springs cause the re-engagement of the plate 13 with the bottom plate 4. When the partition is to be removed, it is simply necessary to slide it to the rear of the drawer and the whole device is then lifted through the opening 2'.

It is thought from the foregoing that the

advantages and novel features of my invention will be readily apparent.

I desire it to be understood that I may make slight changes in the construction and 5 in the combination and arrangement of the several parts, provided that such changes fall within the scope of the appended claims.

I claim as my invention:

1. In combination with a drawer having 10 a slot in its bottom, a box-like track secured to the under side of the drawer and communicating with the slot, a partition having a portion extending into said slot, a plate connected with the said portion and 15 located in the box-like track, said track and plate having corrugations therein, spring means on the partition above the plate engaging with the top of the track for forcing the corrugated plate into engagement with 20 the corrugations on the track and said drawer having an opening in its rear, through which the plate may be removed.

2. In combination with a drawer having 25 a corrugated surface in one wall, a pair of spaced flanges mounted over this corrugated surface in spaced relation thereto, a partition plate, a member carried by said plate to extend between the flanges and having a portion of its surface corrugated for inter- 30 fitting engagement with the corrugated surface, and resilient members mounted on said member to engage the flanges to normally retain said member in engagement with the corrugated surface and thereby

retain the partition plate in adjusted position. 35

3. A sliding drawer partition including a plate, a member extending from said plate having one end enlarged and corrugated, and having a recess at each end of said enlarged portion, and a pair of angular spring members each having one terminal inserted in a recess to dispose the other terminal in a position extending in diverging relation to the enlarged portion of the member, as 40 45 and for the purpose set forth.

4. In combination with a drawer having a corrugated surface in one wall, a pair of flanges mutually spaced and located over the corrugated surface in spaced relation thereto, a plate, a member extending from said plate and into the space between the flanges with the projecting end of the member enlarged and corrugated to bear against the corrugated surface of the wall, said enlarged portion having a recess in each end, and a pair of angular resilient members, each having one terminal inserted in a recess, the other terminals extending away 50 55 from the enlargement to engage the flanges to normally retain the enlarged portion in engagement with the corrugated surface.

In testimony whereof I affix my signature in presence of two witnesses.

SAM NUSSEY.
